UNITED STATES PATENT OFFICE.

AMEDEE J. BENJAMIN, OF VALLEY FALLS, RHODE ISLAND.

DESIGN FOR A HAND SCREW OR CLAMP.

SPECIFICATION forming part of Design No. 13,690, dated March 6, 1883.

Application filed December 7, 1882. Term of patent 14 years.

To all whom it may concern:

Be it known that I, AMEDEE J. BENJAMIN, of Valley Falls, in the county of Providence and State of Rhode Island, have invented and 5 produced a new and original Design for Hand Screws or Clamps, of which the following is a specification.

Reference is to be had to the accompanying drawing, forming part of this specification, in 10 which the figure is an elevation of a hand screw or clamp showing my improved design.

Heretofore hand screws or clamps—such as are used by carpenters, cabinet-makers, and others for holding their work together—have 15 been made with straight backs parallel with the faces of the jaws.

My design consists in making the backs of the jaws of curved form, the outline of which, when viewed in elevation, as in the drawing, 20 forms a graceful convex configuration extending from the rear end of the jaw to the bevel of the nose end thereof, said convexity having its greatest projection at or about the central portion of the jaw, at or near where the 25 center screw of the device passes through.

A A are the jaws, which may be said to constitute the frame of the device; B, the center screw, and C the end screw. The inner faces, 30 b, of the jaws are of straight configuration, as usual, and their noses or front ends, d, of the ordinary beveled form; but the backs of the

jaws are made with a graceful convex sweep or configuration, e, extending from the rear ends, f, to the forward part, g, at which point the convexity terminates and the ordinary end 35 level d joins the convexity. The greatest projection or convexity of the curved back e is intended to be at or about the central portion of the jaws A, where the ordinary center screw, B, intersects it. This curved or convex configuration of the backs of the jaws presents to the eye a much more desirable and graceful form for the jaws than the common form of jaws heretofore used in hand-screws, the backs 40 of which are made straight and parallel with 45 the faces of the jaws.

I claim—

1. The within-described design for the form or configuration of hand screws or clamps, which consists in the backs of the jaws made 50 of convex form, as herein shown and described.

2. The design for a hand screw or clamp herein shown and described, the same consisting in having the backs of the jaws made with a convex form or configuration, the greatest 55 projection of the convexity being about where the center screw of the device passes through the jaws, as set forth.

AMEDEE J. BENJAMIN.
